E. O. SCRIVEN

ELECTRIC CIRCUITS

Filed July 16, 1919

Inventor:
Edward O. Scriven.

by J. P. Roberts Atty.

UNITED STATES PATENT OFFICE.

EDWARD O. SCRIVEN, OF NEW YORK, N. Y., ASSIGNOR TO WESTERN ELECTRIC COMPANY, INCORPORATED, OF NEW YORK, N. Y., A CORPORATION OF NEW YORK.

ELECTRIC CIRCUITS.

Application filed July 16, 1919. Serial No. 311,166.

To all whom it may concern:

Be it known that I, EDWARD O. SCRIVEN, a citizen of the United States, residing at New York, county of New York, State of New York, have invented certain new and useful Improvements in Electric Circuits, of which the following is a full, clear, concise, and exact description.

This invention relates to electric circuits and more particularly it relates to repeater circuits wherein filters are employed to eliminate undesired frequencies.

As is well known in the art, undesirable frequencies in a signaling system may be eliminated by inserting electric filters therein composed of inductance and capacity of such values as to allow only the desired frequency range to pass therethrough. Thus if it is desired to eliminate all frequencies above a certain value, while transmitting all frequencies below that value, the filters should be composed of a plurality of sections each comprising series inductance and shunt capacity of such values as may be determined by reference to the Campbell Patent No. 1,227,114 of May 22, 1917.

It has been found, however, in the use of such a filter that its attenuation and its impedance characteristics within its transmission range vary somewhat with the frequency. This variation in some cases is undesirable particularly in repeater circuits wherein a filter of only a few sections is employed and wherein any distortion due to the unequal attenuation of the filter is amplified thereby increasing the distortion still further.

In accordance with this invention, this variation of the attenuation and the impedance characteristics of the filter with frequency is avoided by terminating the filter in a special network so constructed, as hereinafter described, as to correct the distorting tendencies of the filter.

This correcting net-work preferably consists of a resistance in series with a resonant circuit comprising inductance and capacity. If we represent the inductance and capacity of one full section of the filter by the charac-

ters L_o and C_o , it has been found that the value of the resistance in the net-work should be equal to

$$\sqrt{\frac{L_o}{C_o}}$$

the value of the capacity should be $\frac{1}{15} C_o$ and the inductance $\frac{1}{15} L_o$. It is also preferable that this network be connected to a section of the filter that has only $\frac{1}{10}$ the capacity of a full section of the filter. The filter terminating in such a net-work as above described transmits current within its transmission range with substantially equal attenuation regardless of the frequency. When the correcting network has the values above defined, its impedance is approximately the same as the impedance of the remainder of a filter of infinite length of the type associated with the net-work.

For a better understanding of this invention, reference is made to the following detailed description taken in connection with the accompanying drawing which illustrates the preferred circuit arrangement of this invention.

Referring to the drawing, interposed between the loaded line 3 and the amplifier 4, is a filter comprising inductances 5 to 12 inclusive and condensers 13 to 16 inclusive. This filter terminates in a net-work composed of a winding 20 of transformer 21 and the resonant circuits consisting of inductance 22 and capacity 23, and inductance 24 and capacity 25 respectively. The value of capacity 16 in the last section of the filter should be only approximately $\frac{1}{10}$ of the capacity of condenser 15, which represents the total capacity of a section of the filter. Condensers 23 and 25 which are included in the net-work should each be equal to twice the value, $\frac{1}{15} C_o$ noted above for the capacity of the correcting net-work, since the two condensers are connected in series and therefore have an effective capacity of $\frac{1}{15} C_o$. Similarly each of the inductances 22 and 24 should be equal to $\frac{1}{2}$ the value noted above for the inductances of the correcting net-work that is, each should be $\frac{1}{20}$ of the sum

- of inductances 9 and 10 which sum represents the total inductance of one full section of the filter. Two resonant circuits are employed in the preferred circuit arrangement in order 5 to preserve the symmetry of the two sides of the line. If desired, however, the inductance and capacity of this network may be inserted in one resonant circuit instead of being divided between two resonant circuits.
- 10 Thus inductance 24 and capacity 25 may be omitted, in which case the value of capacity 23 would be halved and inductance 22 would be doubled. Winding 20 of transformer 21 should be so designed that its impedance 15 represents a resistance of a value equal to

$$\sqrt{\frac{L_0}{C_0}}$$

As the example of the values this correcting network may have, it may be stated that in a particular case where the filter was designed to eliminate frequencies above 2000 cycles per second and the inductance per section of the filter was 0.138 henrys 25 and the capacity per section was 0.149 microfarads, condensers 23 and 25 of the network had a capacity of 0.158 microfarads, inductances 22 and 24 each had a value of 0.027 henrys and the effective resistance of 30 winding 20 was 960 ohms.

With the capacity, inductance and resistance of the correcting network adjusted as above described, the combination of the filter and the network will transmit with 35 substantially equal attenuation to amplifier 4 all currents from line 3 of frequencies within the transmission range of the filter. Also the impedance characteristics of the filter, as measured from line 3, will be substantially independent of the frequency 40 within the transmission range. If desired, the amplified signals in the output of amplifier 4 may be further amplified by a second amplifier 30 before being impressed upon 45 the terminals of the outgoing line 31.

It is to be understood that this invention is not limited to the particular circuit arrangement above described, but that it may be variously modified without departing in 50 anywise from the spirit of this invention, as defined in the appended claims.

What is claimed is:

1. In an electric system, means for simulating the impedance of a filter of infinite length, said means comprising a filter of finite length and a network simulating the impedance of the remainder of said filter of infinite length for a wide range of the frequencies freely transmitted by said filter.
  2. In an electric system, a filter comprising a plurality of similar sections, each section containing inductance and capacity, one of said sections having an electrical characteristic of a value $\frac{1}{2}$ the value of
- said characteristic in another of said sections, and a network comprising inductance, capacity and resistance connected to said first mentioned section, the elements of said network having values dependent upon the values of the series and shunt elements of a section of the filter for equalizing the transmission of a band of frequencies.
3. A wave filter of finite length which offers substantially equal attenuation to all frequencies within the transmission range, 75 said filter comprising a plurality of similar sections, and a network for equalizing the transmission of all frequencies within the transmission range, said network comprising an inductance, a separate resistance effectively in series with said inductance, and capacity in shunt with said inductance.
4. In an electric system, a filter comprising a plurality of similar sections, one of said sections having an electrical characteristic of a value a fractional part of the value of said characteristic in another of said sections, and a network connected to said first mentioned section, the elements of said network being so proportioned with respect to the filter that the impedance of the filter over substantially the entire range of transmission will appear to be pure resistance.
5. In a transmission circuit, a line, receiving terminals therefor and means for preventing undesired frequencies from being impressed on said terminals while offering substantially equal attenuation for all frequencies within a given range, said means comprising a wave filter of a plurality of similar sections and a terminating network connected to an end section of said filter having an electrical value only a fractional part of the corresponding value in another section of said filter, said network being so proportioned with respect to said filter that the attenuation of said filter over a given range of free transmission is made substantially constant.
6. In an electric system, a line, receiving terminals therefor, and means for preventing undesired frequencies from being impressed on said terminals while offering substantially equal attenuation for all frequencies within a given range, said means having an impedance simulating the impedance of a wave filter of infinite length for a wide range of the frequencies freely transmitted by said means, and comprising a filter of finite length and a network simulating the impedance of the remainder of said filter of infinite length.
7. In combination, an electric wave filter of a plurality of similar sections each comprising a shunt capacity and a network connected thereto for maintaining the attenuation of all frequencies within the transmission

- range substantially constant, said network being connected to a section of said filter having a shunt capacity approximately equal to eight-tenths the shunt capacity in a full 5 section of said filter.
8. In an electric system, a line, receiving terminals therefor, and means for preventing undesired frequencies from being impressed on said terminals while offering substantially equal attenuation for frequencies within the transmission range, said means comprising an electric filter of a plurality of similar sections, each comprising inductance and capacity and an electrical network, said network comprising an inductance, and impedance in series with said inductance and a capacity in shunt to said inductance, said inductance, capacity and impedance having such electrical values that 10 the equality of transmission through said filter and network is improved thereby.
9. In an electric system, a line, receiving terminals therefor, and means for preventing undesired frequencies from being impressed on said terminals while offering substantially uniform impedance for frequencies within the transmission range, said means comprising an electric filter and an electrical network, said network comprising 15 a resonant circuit and the primary winding of a transformer, said winding being in series with said resonant circuit, the secondary of said transformer being associated with said receiving terminals.
10. In an electric system, a line, receiving terminals therefor and means for preventing undesired frequencies from being impressed on said terminals while offering substantially equal attenuation for frequencies 20 within the transmission range, said means comprising a filter and an electrical network, said filter comprising a section having predetermined electrical characteristics and a second section having an electrical characteristic $\frac{1}{6}$ the value of the corresponding electrical value of said first section, said network comprising a resonant circuit and an impedance connected to said 25 second section.
11. In an electric system, a line, means for amplifying currents from said line, means interposed between said line and said first means for preventing undesired frequencies from being impressed on said first means while offering substantially equal attenuation for frequencies within the transmission range, said means comprising a filter and a network, said network comprising a resonant circuit and a primary winding 30 of a transformer, the secondary of said transformer being associated with said first means.
12. In an electric system, a line, means connected to a terminal of said line for simulating the impedance of a filter of infinite length for a wide range of frequencies within the transmission band of the filter, said means comprising a filter of finite length and a lumped network for simulating the impedance of the remainder of said filter of infinite length and a vacuum tube repeater associated with said network. 65
13. A wave filter of a plurality of similar sections in combination with a network simulating the impedance of the corresponding infinite filter, said network comprising an inductance, a resistance in series with said inductance, and a capacity in shunt to said inductance. 75
14. In an electric system, a line, receiving terminals therefor, and means for preventing undesired frequencies from being impressed on said terminals while offering substantially a uniform impedance for frequencies within the transmission range, said means comprising an electric filter and an electrical network, said network comprising an inductance, an impedance in series with said inductance and a capacity in shunt to said inductance. 80
15. In combination, an electric wave filter of a plurality of sections and a network connected thereto, said network being connected to a section of said filter having an electrical characteristic of a value approximately eight-tenths the value of said characteristic in another section of said filter, and being so proportioned with respect to the filter that the impedance of the filter for all frequencies within the transmission range is substantially uniform. 95
16. A line, a filter therefor comprising inductance elements in series with the line, capacity elements in shunt to the line, and a network for maintaining the attenuation of all frequencies within the transmission range of said filter substantially equal, said network comprising a resonant circuit and a resistance effectively in series with the line. 100
17. In combination, a transmission line, a lumped electrical network for said line comprising a plurality of similar recurring sections, said network having a non-uniform impedance for a certain range of impressed frequencies and a second network associated with said first network for making more uniform the impedance transmission through said first network, said second network comprising a parallel resonant circuit effectively in series with a substantially pure resistance. 115

In witness whereof, I hereunto subscribe my name this 11th day of July A. D., 1919.

EDWARD O. SCRIVEN.
